UNITED STATES PATENT OFFICE.

CHARLES FRED TOPHAM, OF COVENTRY, ENGLAND, ASSIGNOR TO COURTAULDS LIMITED, OF LONDON, ENGLAND.

APPARATUS FOR SIZING TEXTILE FIBERS OR THREADS.

Application filed April 2, 1926, Serial No. 99,431, and in Great Britain June 23, 1925.

This invention relates to the sizing of textile material such as threads or fibers, and in particular to machines for the said purpose, and is especially adapted for use in the sizing of artificial silk warps. In sizing such warps the artificial silk threads are generally drawn off one horizontal roller and pass over a second horizontal roller, the lower part of which dips into a bath of the sizing solution. The threads having thus taken up a certain quantity of the sizing solution, pass over a heated plate in order to dry them, and are then wound onto a third horizontal roller, generally termed a warp beam. Such warp

10 rollers or warp beams often contain a very large number of threads, usually many hundreds and often thousands of such threads being wound parallel on one such roller or beam.

When passing a large number of threads over the second roller, which is dipping into the sizing solution, hereinafter referred to as the sizing roller, it sometimes happens that some of the threads are either not at all or only insufficiently covered or impregnated 25 with the sizing solution. Attempts have been made to avoid this by using another roller at the top of the sizing roller, for the purpose of pressing the threads into the sizing solution with which the sizing roller is coated 30 and also, to a certain extent, spreading out the filaments of which each thread is composed, thus allowing the sizing solution to impregnate the threads. Such top roller, however, has not generally proved successful 35 when artificial silk is being sized, since even if the top roller be coated with a layer of rubber, it is found that the pressure is too great for the delicate artificial silk threads, and the threads are broken or otherwise 40 damaged.

I have now discovered that the sizing of artificial silk threads or fibers (hereinafter referred to as threads) can be carried out very successfully if a top roller of special construction be employed to press the threads onto the sizing roller. The top roller, according to my invention consists of a central rod of hard material, such for example as iron, surrounded by a cylinder of a resilient 45 material, such for example as rubber, a space being left between the hard central rod and the outer resilient cylinder. Into this space I insert a larger or smaller quantity of liquid, such for example as water. This compound 50 roller, when used as the top roller on the

top of the sizing roller, is sufficient to press the threads down into the sizing solution, particularly as the pressure between the two rollers causes a small pool of sizing solution to collect at their point of contact, thus assisting in the impregnation of the threads. The roller itself, however, owing to its special construction is so resilient that any knots on the threads pass easily between the rollers, without being dragged or broken.

It is generally preferred to give both the sizing roller and the top roller a positive drive, so that the surfaces of the two rollers travel at the same peripheral speed, although if desired the top roller need not be positively rotated.

I will describe the invention with reference to the accompanying drawings which illustrate by way of example how the invention may be carried out in practice, but the invention is not limited to the apparatus described and shewn.

Figure 1 represents diagrammatically apparatus in section according to this invention shewing the course of travel of the thread, 80 while Figure 2 is a longitudinal section of a compound top roller according to this invention, and Fig. 3 is a longitudinal section of another roller according to this invention.

Referring to Figure 1, A is the first roller 85 or warp beam from which the threads X are being unwound, passing over the sizing roller B which dips into the trough of sizing solution C. D is the top roller according to this invention, and is shewn as being filled about 90 one-third with water.

After passing between the sizing roller and the top roller the threads travel over a heated box E where they are dried and then through a reed F, being finally wound on a 95 third roller or warp beam G.

In Figure 2, which illustrates a compound top roller according to this invention, H is the central rod, on each end of which is a circular flange J. K is a cylinder of resilient 100 material such as a rubber tube fastened to one of the flanges J at each end and leaving a space L between the peripheral tubing and the central rod H. M is a screw stopper on the removal of which a larger or smaller 105 amount of water or other suitable liquid can be poured into the space L. The end of the central rod H is provided with a gear wheel N by means of which it is driven.

In Figure 2 the central rod is shewn as 110

being continuous from end to end of the roller, but if desired the middle portion of this rod may be omitted provided means are employed for positively driving each end of the roller at the same speed.

As a general rule the top roller is preferably longer than the total width occupied by the threads on the sizing roller, so that the rubber which is immediately under its end 10 supports or flanges does not come into contact with the threads which are being sized. The remaining portions of the roller, by reason of the resiliency of the material and the lack of support from the interior, are subject 15 to slight deformation by the liquid within the roller. This deformation, coming always at the bottom, causes the contact with the sizing roller to extend over an appreciable area.

What I claim is:—

20 1. In apparatus for sizing textile threads, a sizing roller, associated means for supplying sizing thereto, means for passing over the

sizing roller a group of threads of delicate structure such as artificial silk, in combination with a roller for pressing the threads 25 upon the sizing roller, said press roller comprising a hollow cylinder of resilient material and a weighting liquid contained within the roller.

2. In apparatus for sizing textile threads, 30 a sizing roller, associated means for supplying sizing thereto, means for passing over the sizing roller a group of threads of delicate structure such as artificial silk, in combination with a roller for pressing the threads 35 upon the sizing roller, said press roller comprising a hollow cylinder of resilient material and a weighting liquid of less volume than the interior of the hollow cylinder contained within the roller.

40 In testimony whereof I have signed my name to this specification.

CHARLES FRED TOPHAM.
